United States Patent Office.

HERMANN BERGER, OF MARTHALEN, SWITZERLAND.

Letters Patent No. 95,186, dated September 28, 1869.

IMPROVEMENT IN EMBROIDERING-MACHINE.

The Schedule referred to in these Letters Patent and making part of the same.

To all whom it may concern:

Be it known that I, HERMANN BERGER, of Marthalen, canton of Zurich, Switzerland, have invented a new and improved Multiple Embroidering-Machine; and I do hereby declare that the following is a full, clear, and exact description thereof, which will enable others skilled in the art to make and use the same, reference being had to the accompanying drawings, forming part of this specification.

Figure 1 represents a side view, partly in section, of my improved embroidering-machine.

Figure 2 is an end view of the same.

Similar letters of reference indicate corresponding parts.

The object of this invention is to construct an embroidering-machine which can be used on gauze or other fabric, in such manner that one or more pairs of curtains or other articles can at once be embroidered thereon, with the design in reverse. Thereby a very large amount of labor is saved, as, in the machinery heretofore in use, but one single piece could be treated, and, as for the reverse position required on every pair of curtains, new designs had to be gotten up.

My invention consists in providing the swinging sewing-frame with one or more pairs of needles, and with one or more pairs of hooks, or their equivalents, one needle of each pair working from above, and the other from below the piece of fabric which is to be embroidered by it.

A separate sheet of fabric is stretched on a fixed or adjustable frame between every needle and its hook. Both pairs move simultaneously, and as one embroiders its fabric on the upper side, the other applies the ornamentation to the under side, both actions, however, being regulated by the motion of the swinging frame. Then the same design is applied to both fabrics, one to the upper and the other to the under side; thereby the design is reversed on the two.

A, in the drawing, represents a swinging frame of an embroidering-machine.

It has on its inner end projecting lugs *a a*, by means of which it is pivoted to a suitable stationary frame.

A vertical shaft, B, hung in the frame A, is in line with the pivots of the same, and receives its motion from suitable mechanism of the stationary frame, in whatever direction the said frame may be turned.

From the inner vertical bar *b* of the frame A, project three horizontal bars, *c d*, and *e*, the bar *d* being sideways between *c* and *e*, as shown in fig. 1.

Each of these bars has at its outer end a vertical arm, *f*, and these several arms have horizontal lugs in which the several vertical tubes, C, D, and E E', are hung to revolve in their bearings.

The tube C is held on the upper arm *c*, the tube D on the lower arm *e*, and the tubes E E' on the middle arm *d*, some distance apart.

The axes of the four aforesaid tubes are all in line with each other, and all the tubes, except E, carry toothed wheels, *g g*, that mesh into similar wheels on horizontal axles F, which are again geared into wheels *h* on a vertical axle, G.

The tubes E E' carry pinions, *i i*, that mesh both into other pinions, *j j*, of an arbor, R.

Thus all the four tubes are connected with each other, and all will therefore turn on their own axes in the same direction, and simultaneously, when one is turned.

H H' are the embroidering-hooks. They are pivoted to ears that project from the ends of the tubes, E E' respectively, and are connected with each other by a rod, I, which passes through both tubes E E', as shown.

The rod I carries a cross-head, L, which moves in guides *m*, formed on the frame A, and which is connected with a crank-pin or eccentric, *n*, formed on the front end of a horizontal shaft, J, said shaft receiving its motion by gearing from the shaft B, as shown.

As said shaft is revolved, the cross-head L receives reciprocating motion, and acts on both hooks, H H', to oscillate them simultaneously.

L L' are the two needles, fitted respectively into holders M M' that are placed through the tubes C D.

The holder M' receives reciprocating motion from levers N N' that are acted upon by eccentrics on shafts O O', said shafts gearing also into B.

Thus the needles and the hooks are moved simultaneously.

The needles are moved in the same direction; that is to say, both move up at the same time, and down also.

A small shield, P, is arranged on the arm *f* of *c*, around the needle L, and one on the arm *f* of *e*, around the needle L', each serving to hold the stretched fabric the proper distance from the hook.

A separate sheet of fabric is stretched between each needle and its hook.

As the machine is set in operation, the needles apply their threads to their respective fabrics; the upper needle L applies its thread to the upper surface of the fabric, and the lower needle applies its thread to the lower surface, both hooks forming the requisite stretches on the sides opposite to the needles.

Either one of the needles can be thrown out of gear by means of suitable levers.

When the fabric is stretched in the two places, and a pattern above the upper fabric, the frame A is

swung on its pivots to carry the needle along the required lines.

The design is then embroidered in reverse order on both fabrics.

I do not claim the mechanism for making the stitches, nor the frame A, nor anything in the construction of the machinery on this apparatus.

Having thus described my invention, what I claim as new, and desire to secure by Letters Patent, is—

1. A multiple embroidering-machine, substantially such as described, provided with one or more pairs of hooks and needles working from above and below the

cloth, in order to apply the same design in reverse order to two or more pieces of fabric, substantially as herein shown and described.

2. The combination with each other of the two embroidery-hooks H H' attached to the rod I, so as to move simultaneously below and above sheets of fabric, as set forth.

The above specification of my invention signed by me, this 30th day of June, A. D. 1869.

HERMANN BERGER.
